DOUBLE LOCKER

Joop M. Van Ryn, Whitby, Ontario, Canada, assignor to
The Pedlar People Limited, Oshawa, Ontario, Canada, a corporation of Canada

Filed May 28, 1968, Ser. No. 12,109

Term of patent 14 years

Int. Cl. D6—01
U.S. Cl. D33—19

FIG. 1

The side of the locker not shown is like the side shown while the back is conventionally flat and unornamented.

I claim:

The ornamental design for a double locker, as shown and described.
